UNITED STATES PATENT OFFICE.

JAMES HATTEN HOWARD, OF JACKSONVILLE, FLORIDA.

DISPENSING-CAN CLOSURE.

1,343,825.

Specification of Letters Patent. Patented June 15, 1920.

Application filed July 10, 1919. Serial No. 309,974.

To all whom it may concern:

Be it known that I, JAMES H. HOWARD, a citizen of the United States, and a resident of Jacksonville, in the county of Duval 5 and State of Florida, have invented a new and Improved Dispensing-Can Closure, of which the following is a full, clear, and exact description.

This invention relates to improvements in dispensing can closures, an object of the invention being to provide a device of the character stated, which, when operated, opens the outlet of the can, causes a forceful ejection of a portion of the contents 15 thereof and then closes the outlet.

A further object is to provide a dispensing can closure which causes a uniform discharge at each operation and prevents wastage through careless operation, such as 20 is customary with the ordinary can closure.

With these and other objects in view the invention consists in certain novel features of construction, and combinations and arrangements of parts, as will be more fully 25 hereinafter described and pointed out in the claims.

In the accompanying drawings—

Figure 1 is a view in end elevation illustrating my improvements;

Fig. 2 is a view in side elevation; and Fig. 3 is a fragmentary view in longitudinal section showing the can in inverted position.

1 represents a receptacle, such as an ordinary powder can for tooth powder, toilet powder, or any other suitable material, having an outlet 3 in its closed end 2. The outlet 3 is located at one side of the center of the end 2, and a closure 4 normally closes the outlet 3. This closure 4 is preferably in the form of a lever fulcrumed between its ends on a pin 5 supported in brackets 6 secured to the end 2, and a spring 7 is located between the closure 4 and the end 2 40 normally holding the closure in its closed position covering the outlet 3. An ejector 8 is secured to the closure 4, is located mainly within the receptacle 1 and movable at its narrower portion through a slot 9 in the end 2 communicating with the outlet 3.

The closure 4 and the ejector 8 are of 50 general spoon or paddle shape so that when either is against the end 2, the outlet 3 will be effectually closed. The normal positions of the closure 4 and the ejector 8 are indicated by full lines in Fig. 3, and the other 55 extreme positions are indicated by dotted lines in the same figure.

The operation is as follows: when the closure 4 is moved on its pivot 5 from the position shown in full lines to that in dotted 60 lines in Fig. 3, a given quantity of powder from the can will be allowed to pass through the outlet 3 and will be forcibly ejected by means of the ejector 8, which then closes the outlet 3. When the closure 4 65 is released, the spring 7 will return the parts to normal position.

Various slight changes may be made in the general form and arrangement of parts described without departing from the invention, and hence I do not limit myself to the precise details set forth but consider myself at liberty to make such changes and alterations as fairly fall within the spirit and scope of the appended claims. 75

I claim:

1. A device of the character described, comprising a receptacle having an outlet therein, and a slot communicating with the outlet, a closure pivotally supported on the 80 receptacle, an ejector secured to the closure located mainly within the receptacle and movable in the said slot, and a spring normally holding the closure over the outlet.

2. A device of the character described, 85 comprising a receptacle, an end on the receptacle having an outlet therein, brackets on said end, a closure constituting a lever pivotally supported between its ends by said brackets, one end of said closure normally 90 covering the outlet, a spring interposed between one end of the closure and the receptacle end, and a combined ejector and closure secured to the first-mentioned closure and located mainly within the receptacle.

JAMES HATTEN HOWARD.
